UNITED STATES PATENT OFFICE.

OSCAR ANDERSON, OF CHICAGO, AND CARL NELSON, OF CHICAGO HEIGHTS, ILLINOIS.

TUMBLER-WASHER.

1,124,239.

Specification of Letters Patent.

Patented Jan. 5, 1915.

Application filed March 16, 1912. Serial No. 684,329.

To all whom it may concern:

Be it known that we, OSCAR ANDERSON and CARL NELSON, citizens of the United States, residing, respectively, at Chicago and Chicago Heights, in the county of Cook and State of Illinois, have jointly invented certain new and useful Improvements in Tumbler-Washers, of which the following is a specification.

10 This invention relates to improvements in tumbler washers and its object is to produce a device of this class that is efficient in operation and that cleanses a tumbler inside and outside at one and the same time and 15 that does the work thoroughly. Simplicity and cheapness of manufacture are other objects.

With the foregoing and other objects in view the invention consists in the combination and arrangement of parts to be fully described in the following specification, pointed out in the claims and illustrated in the accompanying drawings which form a part of the specification and in which—

25 Figure 1 is a vertical sectional elevation of our improved tumbler cleaner attached to a water faucet taken on line 3—3 of Fig. 4. Fig. 2 is a view of the washer in elevation. Fig. 3 is an inverted plan. Fig. 4 is 30 a top plan showing the water wheel with drum removed. Fig. 5 is a modification.

Like reference characters indicate corresponding parts throughout the several views.

35 1 is a water faucet to which our improved washer is designed to be attached through the medium of the threaded pipe 2 that is made integral with the drum 3 which is provided with an annular prolongation or lip 40 4 at its flared extremity. The periphery of the lip 4 is retained within the hooked or curved projections 5 of a cylindrical casing 6 that is open at each end and that is provided near its upper extremity with a plurality of apertures through each of which 45 one end of a brush 7 projects, the other end of the said brush extending longitudinally of the casing 6 and passing out beneath the same as at 8.

50 Within the drum 3 beneath the faucet 1 is a water wheel 9 mounted upon a shaft 10 that is supported in a bearing 11 the ends of which are secured in the drum 3.

55 12 is a circular plate secured by means of a block 13 and pin 14 to the shaft 10 within the drum 3 near its flared extremity and

somewhat less in diameter than the drum at this point. Beneath the plate 12 is a large circular plate 15 apertured as at 15^a the periphery of which rests in the projections 5 of the casing 6 and which is riveted or otherwise secured to the lip 4 of the drum 3 as shown in Fig. 1.

At 16 a bearing is formed in the plate 15 for the shaft 10 which shaft extends through this plate and also through a perforated plate 17 which is circular in shape and the periphery of which rests freely upon an annular shoulder 18 formed in the casing 6; below the plate 17 within the casing 6 the shaft 10 receives one extremity of a brush shaft 19 to which a plurality of brushes 20 are secured. The shaft 10 is so supported in the bearing 11 as to be capable of longitudinal movement to a certain degree and pressure exerted in an upward direction upon the brush shaft 19 will raise the shaft 10 until a shoulder 21 formed on this shaft comes in contact with the bearing 11. When this shaft is raised vertically 75 the plate 12 is also raised vertically thus permitting the water that runs off the water wheel to pass beneath the last named plate and through the apertured and perforated plates upon the revolving brushes. A tumbler to be washed is inserted into the lower end of the casing 6, the brushes 20 passing into the tumbler and the brushes 7 being brought into contact with the exterior of the same, the tumbler being held stationary in 80 the hand. The water falling upon the wheel 9 rotates the same and also the shaft 10 and plate 12 secured to that shaft and the shaft 19 with brushes 20. When the bottom of the tumbler is brought up against the 85 brushes 20 or when the upper edge of the tumbler raises the plate 17 the shaft 10 is raised and with it the plate 12 thus admitting the water to the revolving brushes and cleansing the tumbler. By rotating the 90 tumbler in the hand the brushes 7 will cleanse it externally, since these brushes are secured to the casing and immovable with relation thereto.

In Fig. 5 a modification is shown. A perforated plate A is provided with a pair of spring hinges or snap hinges B, one of these hinges having a short leaf C. The hinges B, oppositely disposed and secured to the plate A, are adapted to frictionally secure 105 said plate to the casing 6. A tumbler may be placed upon plate A while detached

from the casing and when said plate is secured by the hinges to the casing as illustrated the tumbler will be disposed entirely within the casing upon the plate. Retained in this position it is cleansed internally by the revolving brushes 21; the tumbler may be removed by removing the plate A entirely or removing one of the hinges from contact with the casing permitting said plate to drop away from the casing at this point so that the tumbler may be manually removed.

What is claimed is:—

1. In a tumbler washer, the combination with a water faucet, of a drum secured thereto, an annular lip made integral with the flared extremity of said drum, a casing, hooked projections made integral with said casing engaging the said annular lip, a longitudinal rotary shaft mounted in the said drum and projecting therebeyond and capable of limited vertical movement, a water wheel arranged on said shaft, an apertured plate circumferentially seated in the aforesaid hooked projections and formed with a bearing for the said longitudinal shaft, means secured to the said longitudinal shaft for normal contact with the said apertured plate, a perforated plate seated in the said casing below the said apertured plate pierced by the said longitudinal shaft, a brush shaft connected to the said longitudinal shaft and brushes arranged on said brush shaft.

2. In a tumbler washer connected to a water faucet, a drum, an annular lip made

integral therewith, a casing connected to said drum, a shafted water wheel capable of limited vertical movement mounted in said drum receiving water from said water faucet, an apertured plate mounted in said casing beneath said water wheel, a perforated plate in said casing beneath said apertured plate, a rotary brush in said casing operatively connected to said shafted water wheel and a plate normally disposed upon said apertured plate operatively connected to said shafted water wheel.

3. In a tumbler washer connected to a water faucet, a drum, an annular lip made integral therewith, an apertured casing connected to said annular lip, brushes carried by said apertured casing, a shafted water wheel capable of limited vertical movement mounted in said drum to receive water from said faucet, an apertured plate carried by said casing beneath said water wheel, a plate normally in contact with said apertured plate operatively connected to said shafted water wheel, a perforated plate beneath said apertured plate, rotary brushes operatively connected to said water wheel and a base removably connected to said casing.

In testimony that we claim the foregoing as our own we have hereto affixed our signatures in the presence of two subscribing witnesses.

OSCAR ANDERSON.
CARL NELSON.
